DRYING SYSTEM

Ernest A. Stienen, Peekskill, N. Y.

Application July 21, 1951, Serial No. 237,929

1 Claim. (Cl. 34—104)

1

My invention relates to drying systems, particularly to apparatus for the liquid extraction and drying of yarn in package form, and has for its principal object to provide a combined extractor and dryer for processing yarn in package form.

Heretofore, as far as applicant is aware, it has been customary to provide an extraction vessel including blower, motor, and heater for withdrawing the liquid from the packages and a separate drying vessel including its blower, motor, and heater for drying the packages following the extraction step. Both extraction and drying vessels are spaced from each other thereby requiring labor in moving the carrier containing the packages from the extractor vessel to the drying vessel. Since the yarn is heated during the extraction process, a substantial amount of heat is lost during the transfer from one vessel to the other, which heat loss must be replenished by the heating unit associated with the drying vessel. Further, the tendency has been in the past to leave the carrier with its packages in the extraction vessel for a period of time following extraction of the liquid, in order to do other work, and then move the carrier to the drying vessel. This also consumes not only heat but also increases the time interval required for the overall extraction and drying of the yarn.

It is thus another object of my invention to overcome the hereinbefore noted disadvantages of the prior art by providing a combined liquid extracting and drying vessel for respectively extracting liquid from and drying the yarn in prompt succession, thereby reducing the time interval, labor (since the yarn remains in the same vessel), space, and equipment costs.

Still another object of my invention is to provide a simple, inexpensive, and practical unit for extracting and dyeing yarn particularly in package form.

Other and further objects will be obvious upon an understanding of the illustrative embodiment about to be described, or will be indicated in the appended claims, and various advantages not referred to herein will occur to one skilled in the art upon employment of the invention in practice.

In accordance with my invention, the foregoing objects are accomplished by providing apparatus comprising, in combination, a combined liquid extracting and drying vessel, a plenum chamber provided with heating means, a pair of conduits each with a self-sealing gate valve interconnecting the vessel and the plenum chamber, a

2

third self-sealing gate valve being disposed in a conduit leading to the sewer for exhausting the liquid during the extracting period, and a blower provided with a suitable motor coupled by a single conduit to the plenum chamber.

A more complete understanding of the invention will be obtained from the following description of a preferred embodiment thereof, taken in conjunction with the accompanying drawings, in which:

Figs. 1 and 2 show top plan and elevation views, respectively, of the extractor-dryer of my invention;

Fig. 3 is a sectional view showing the details of the combined extractor-dryer vessel taken along line 3—3 of Fig. 1 in the direction of the arrows; and

Fig. 4 is a sectional view taken along line 4—4 of Fig. 3 in the direction of the arrows.

Referring now to the drawings, particularly to Figs. 1 and 2, there is shown a combined extracting and drying vessel 10 connected by conduits or ducts 12, 14 with one side of a plenum chamber 16 provided with heating means, such as steam pipes 18, 20 for heating air passing therethrough. The other side of the plenum chamber 16 is connected by a single conduit 22 to a conventional blower discharge member 24 driven by any suitable means, such as a motor 26.

In conduits 12 and 14 are shown individual valves 28, 30, respectively, for opening and closing the passageways through said respective conduits. A third valve 32 is shown in a conduit 34, which interconnects conduit 14 with a sewer, this valve 32 being opened during the liquid extracting period for carrying the liquid air or moisture to the sewer. A fourth valve 36 is optional and is shown in a conduit 38 connecting the conduit 12 with the sewer. Normally, during the drying step, the moistened air is exhausted directly to the atmosphere but in the event that the moistened air must be carried to the sewer, then this fourth valve 36 and conduit 38 are required. While any individual type of valve may be used, applicant has found his self-sealing gate valve most efficient for use in this invention, which gate valve is disclosed in applicant's co-pending United States patent application having Serial Number 234,960 and filing date of July 2, 1951.

Referring now particularly to Figs. 3 and 4, there is shown in greater detail the combined extracting and drying vessel 10 which comprises the usual shell 40 having side openings 42, 44 for the conduits 12, 14, respectively; a bottom 46 and 55 removable top 48 with counterweight 50 (Fig. 2)

is pivotally mounted upon the top for facilitating removal thereof from the shell 40. Within the shell are provided two compartments A and B, compartment A being formed by a duct 52 coupled to conduit 14 at opening 44, the inner end thereof opening into a hollow stand 54 of circular configuration, which stand is rigidly secured to the bottom 46 of the shell. The upper portion of the stand 54 is provided with an annular portion or platform 56 having a centrally disposed opening 58. The stand 54 is also provided at its upper end with a centrally disposed threaded socket 60 supported by gussets 62 secured to the stand 54. The platform 56 is shown carrying a conventional carrier 64 having an inclined bottom 66 with an opening 67 coaxial with opening 58, a spaced horizontal second bottom 68, and perforated hollow tubes 69 shown partially equipped with conventional packages 70. The carrier is also shown equipped with a centrally disposed rod 72 for facilitating removal of the carrier, the lower end thereof being threaded secured to the socket 60. Thus compartment A may be said to comprise the inner portions of duct 52, stand 54, the space between bottoms 66 and 68 and the hollow portion 73 of tubular members 69; while compartment B may be said to comprise the remaining area of shell 40, which is coupled at opening 42 to conduit 12.

The operation of the drying system will now be described, extraction of liquid from the packages being first discussed. Referring to Fig. 1 where solid arrows show the direction of air flow, gate valves 28 and 32 are opened and gate valves 30 and 36 (when used) are closed. The air discharged from blower 24 is passed into plenum chamber 16 via conduit 22 where it is suitably heated by steam pipes 18, 20, after which the heated air is passed via conduit 12 and opened valve 28 into compartment B of the shell 40 (Fig. 3) where it is forced through the packages 70. The moisture or liquid laden air then passes through the hollow portions 73 of the perforated hollow tubes 69 into compartment A and thence via ducts 14 and 34 and opened gate valve 32 into the sewer. It is thus evident that during the extraction period the air is passed through the packages 70 from the outer peripheral surfaces thereof to the inner peripheral surfaces, which may be termed herein for convenience "outside-in."

For the drying operation, valve 30 is opened and valves 28 and 34 are closed. The top 48 is then removed from the shell 40, assuming that it is permissible to exhaust the evaporated air into the atmosphere. However, if it is necessary to exhaust the evaporated air into the sewer, then valve 36 is opened. Referring to Fig. 1, the heated air from the plenum chamber 16 then passes through conduit 14 and opened valve 30 (see dotted arrow) into the compartment A of the shell 40 and thence via perforated hollow tubes 69 through the packages 70 and thence into the atmosphere or sewer via conduit 12 and opened valve 36, as required. It is thus apparent in this instance that during the drying operation the air is passed through packages 70 from the inner peripheral surfaces thereof to the outer peripheral surfaces, which may be termed herein for convenience "inside-out."

From the foregoing, it is readily apparent that

an advance in the art has occurred by combining in one unit both the extraction and drying operations. In the extraction operation free moisture in the so-called liquid stage is removed, while in the drying operation we have what is known as an evaporative condition. To differentiate between the two steps, it is important to note that the resistance of the wound package of yarn, when saturated, offers considerably higher resistance to air flow, in view of its moisture content, than during the drying process. Thus, applicant has found that when the extraction operation is relatively complete, it was possible to reverse the flow so that the direction of heated air from the inside of the package to the outside of the package was readily consummated, since the yarn offered lower resistance to air flow because of the removal of the excess, so-called free liquid.

As various changes may be made in the form, construction and arrangement of the parts herein, without departing from the spirit and scope of the invention and without sacrificing any of its advantages, it is to be understood that all matters herein are to be interpreted as illustrative and not in any limiting sense.

What is claimed is:

A combined extracting and drying machine for processing yarn in package form comprising, in combination, a vessel including a removable cover for extracting liquid from and drying the yarn, said vessel being subdivided into two separate compartments, means including a blower for supplying heated air to the vessel, a plenum chamber including means for heating the air interposed between the blower and the vessel, a single conduit between the blower and the plenum chamber, a pair of conduits between the plenum chamber and the two compartments of the vessel, one of said conduits forming a wall separating the compartments, a valve in each of said pair of conduits for selectively directing heated air into and out of said vessel, perforated tubes supporting said packages disposed and arranged within said vessel whereby the interior of said perforated tubes, interior of said packages and exterior of said packages are in series relation with said pair of conduits, a conduit with a valve connected at one end to one of said pair of conduits between said vessel and the valve associated with said one of said pair of conduits, said last conduit being connected at its other end to a sewer and thereby being adapted to discharge the liquid from the packages during the extracting period while evaporated air is discharged directly to the atmosphere upon removal of the cover during the drying period, the blower in both extracting and drying periods taking in air only from the atmosphere and the vessel discharging liquid only to the sewer and evaporated air to the atmosphere.
